UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 5, 1925. Serial No. 13,371.

My invention relates to drilling mechanisms and more particularly to improved tool retainer means for such mechanisms.

An object of my invention is to provide an improved drilling mechanism. Another object of my invention is to provide an improved hammer drilling mechanism having improved tool retaining means therefor. Still another object of my invention is to provide improved resilient tool retaining means which may be adjusted with facility with a minimum of effort. A still further object of my invention is to provide an improved tool retaining means having an improved resilient mounting therefor wherein the shocks upon the retainer encountered during the drilling operation are readily absorbed and wherein breakage is reduced to a minimum. These and other objects and advantages of my invention will, however, hereinafter more fully appear.

In the accompanying drawings I have shown for purposes of illustration one form which my invention may assume in practice.

In these drawings,—

Fig. 1 is a plan elevation of a forward portion of a hammer drilling mechanism incorporating my improved device, the view being partially in section to facilitate illustration.

Fig. 2 is a side elevation of the mechanism shown in Fig. 1, the view being partially broken away in section.

Fig. 3 is a front end elevation of Fig. 1, my improved tool retainer being shown in a plurality of positions.

In this illustrative embodiment of my invention I have shown a forward portion of a hammer drilling mechanism which may be of any standard form and which herein comprises a chuck housing 1 adapted to receive a usual collared drill steel 2. The chuck housing 1 is provided with lateral lugs 3 through which usual side rods 4 are adapted to pass and these side rods are encircled at their forward ends by coiled springs 5 which act at one end against washers 6 engaging arcuate surfaces 7 formed on the forward surfaces of the lugs 3 while at the other end the springs engage suitable annular washers 8, the tension of the springs being adjusted by means of suitable nuts 9 threaded on the forward ends of the side rods 4. It will herein be noted that the side rods 4 and the springs 5 resiliently maintain the parts of

the drilling mechanism in operative assembled relation, in a well known manner.

In my improved construction it will herein be observed that the forward portion of the chuck housing is provided with laterally disposed longitudinally extending parallel bosses or lugs 10 projecting forwardly from the chuck housing 1 and disposed at substantially right angles to the side rods 4 and these bosses are provided with longitudinally extending parallel bores 11 through which short side rods 12 are adapted to pass. The forward portions of these side rods 12 are provided with squared heads 13 which abut against a transversely disposed retainer yoke 14. As illustrated, the retainer yoke 14 is pivotally mounted, as at 15, on one of the side rods 12 while the other end is provided with an arcuate slot 16 which permits transverse swinging movement of the yoke 14 relative to the other side rod 12. Tension is maintained on the rods 12 by means of coiled springs 17 which encircle rearwardly projecting portions of the side rods 12 and which react at one end against suitable washers 18 engaging the rear surface of the bosses 10 and at the other end against suitable washers 19 engaging adjustable nuts 20 threaded on the rods and by means of which nuts 20 the tension of the coiled springs may be adjusted. As shown, the forward surface of one of the bosses 10 is notched, as at 21, (see Fig. 2) with which a projection 22 formed on the rear surface of the retainer yoke is adapted to cooperate. This notch and projection enables the retainer to be locked in its operative or retaining position.

In the use of my improved retaining means it will herein be noted that when it is desired to remove the steel from the chuck housing the operator grasps the retainer yoke and swings the latter downwardly (see Fig. 3), the projection being released from the notch 21 at that time and the spring 17 compressing upon such release. When the new steel is inserted within the chuck housing the retainer yoke is then swung upwardly until the projection 22 again snaps with in the notch 21, consequently locking the retainer yoke in its operative retaining position.

As a result of my improvement it will herein be noted that improved retaining means are provided wherein the same may be adjusted with facility. It will further

be noted that an improved resilient mounting is provided for the retaining means wherein the constant hammering shocks enacted thereupon are substantially lessened or 5 obviated, both the side rod springs and the retainer springs absorbing the shock. It will also be noted that improved retainer means are provided of an exceedingly simple and rugged character which may be applied to a standard hammer drilling mechanism with a minimum of change and expense.

While I have in this application specifically described one form which my invention 15 may assume in practice, it will be understood that this form of the same is shown for purposes of illustration and that the invention may be modified and embodied in various other forms without departing from 20 its spirit or the scope of the appended claims.

What I claim as new and desire to secure by Letters Patent is:

1. A drilling machine comprising a plurality of members including a chuck housing, means including side rods for holding said members together, tool retaining means comprising lugs formed on said housing, side rods slidable in said lugs, a transversely 25 swingable yoke carried by said rods and swingable in a plane transverse to said side rods, means affording a resilient mounting 30 for said yoke, and locking means comprising interlocking portions on one of said lugs and on said yoke respectively.

2. A drilling machine comprising a plurality of members including a chuck housing, means including side rods for holding said members together, tool retaining means 40 comprising lugs formed on said housing, side rods slidable in said lugs, a transversely swingable yoke carried by said rods and swingable in a plane transverse to said side rods, means affording a resilient mounting 45 for said yoke, and locking means comprising

a locking tooth formed on said yoke and a cooperating tooth receiving notch formed in one of said lugs.

3. A drilling machine comprising a plurality of members including a chuck housing, means for holding said members together, tool retaining means comprising laterally spaced lugs formed on said chuck housing and extending forwardly therefrom, side rods slidably mounted in said lugs, a 55 transversely swingable yoke carried by said side rods and swingable in a plane transverse to said side rods, and means respectively formed on said yoke and on one of said lugs for locking the same in a predetermined position.

4. A drilling machine comprising a plurality of members including a chuck housing, means for holding said members together, tool retaining means comprising lateral lugs formed on said chuck housing and extending forwardly therefrom, side rods 60 slidably mounted in said lugs, tensioning means positioned about said rods at the rear ends of said lugs, a transversely swingable 65 yoke carried by said side rods and swingable in a plane transverse to said side rods, a locking tooth on said yoke, and a cooperating notch in one of said lugs.

5. A drilling machine comprising a plurality of members including a chuck housing, means for holding said members together, tool retaining means comprising lateral lugs formed on said chuck housing and extending forwardly therefrom, side rods 70 slidably mounted in said lugs, tensioning means positioned about said rods at the rear ends of said lugs, means for varying the 75 tension of said springs, a transversely swingable yoke carried by said side rods and swingable in a plane transverse to said side rods, a locking tooth on said yoke, and a cooperating notch in one of said lugs.

In testimony whereof I affix my signature.

ELMER G. GARTIN.
